A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

FIG. 1 is a front view of a display screen with graphical user interface for viewing and installing applications in an electronic mall showing our new design; and,

FIG. 2 is a second embodiment thereof.

The dash-dot broken line showing of a display screen forms no part of the claimed design. The broken line showing of the remainder of the graphical user interface forms no part of the claimed design.
